HOOK FOR LIFTING HOLLOW CYLINDRICAL OBJECTS

Harry Nelson VerSoy, New Orleans, and Robert J. Harris,
Marrero, La., assignors to H. C. Price Co., Bartlesville,
Okla., a corporation of California

Filed Sept. 29, 1965, Ser. No. 87,213

Term of patent 14 years

(Cl. D41—1)

Fig.3.

Fig.4.

Fig.1.

Fig.2.

Fig.5.

FIG. 1 is a side elevational view of a hook for lifting hollow cylindrical objects, showing our new design;
FIG. 2 is a front elevational view thereof;
FIG. 3 is a top plan view thereof;
FIG. 4 is a rear elevational view thereof; and
FIG. 5 is a bottom plan view thereof.

We claim:

The ornamental design for a hook for lifting hollow cylindrical objects, as shown.
